DESIGN FOR A COMPACT OR THE LIKE

Rubin Shatkin, Brooklyn, N. Y., assignor to Aaron Shatkin, Matawan, N. J.

Application June 23, 1945, Serial No. 120,297

Term of patent 7 years

(Cl. D86—10)

To all whom it may concern:

Be it known, that I, Rubin Shatkin, a citizen of the United States and a resident of the Borough of Brooklyn, county of Kings, city and State of New York, have invented a new, original, and ornamental Design for a Compact or the like, of which the following is a specification; reference being had to the accompanying drawing, forming part thereof.

Fig. 1 is a top plan view of a compact showing my new design and

Fig. 2 is a side elevation of said compact.

The design is characterized by the ornamentation on the central portion of the compact best shown in Fig. 1 of the drawing.

I claim:

The ornamental design for a compact or the like, substantially as shown and described.

RUBIN SHATKIN.
